UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

TYPE-WRITING MACHINE.

1,121,044.

Specification of Letters Patent. Patented Dec. 15, 1914.

Application filed August 13, 1912, Serial No. 714,842. Renewed November 13, 1914. Serial No. 872,039.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing Machines, of which the following is a full, clear, and exact description.

This invention relates more particularly 10 to mechanism for vibrating the ribbon to cover and uncover the printing point of visible or front strike typewriting machines.

The primary object of the invention is to 15 provide simple and efficient ribbon vibrating mechanism which is particularly adapted for use in connection with typewriting machines in which the carriage is foldable forward in order that the machine may be 20 more compact when not in use than when in its normal working position to adapt the machine for transportation or other purposes, and which mechanism is so constructed that the parts of the vibrating mechanism 25 always remain in constant registration and coöperation both when the carriage is in its folded and in its working positions; and to provide simple means whereby the 30 said mechanism may be operated by the key-levers when the carriage is in its working position and be moved out of coöperation with said levers when the carriage is in its folded position.

Another object of the invention is to provide 35 simple and efficient mechanism which is adapted to positively move the ribbon different distances to cover and uncover the printing point in order that the ribbon may have a plurality of fields or zones of different colors thereon or which will permit the 40 ribbon to remain inactive in order that stencils may be made.

Other objects of the invention are to provide 45 simple and efficient means which will prevent the ribbon from being thrown too high when the keys are operated with unusual force, and which will positively restore the ribbon to one side of and below the printing point; and to provide means 50 whereby the ribbon vibrator may be readily and easily operated and always held substantially rigid and with little or no play whatever.

A further object of the invention is to

provide a mechanism which is simple in construction and readily accessible and convenient for use, and which mechanism may be substantially entirely assembled away from the machine and readily applied thereto.

A still further object of the invention is 60 to provide mechanism which may be manually adjusted so that in one position the ribbon may remain inactive in order that stencils may be made, in a second position the vibrator operated to present one field of 65 the ribbon to cover and uncover the printing point, and in a third position to increase the throw of the ribbon and thereby present another field to the printing point, and the parts so constructed that the ribbon after 70 printing will be immediately restored to its normal position away from the printing point in order that the printing may be seen.

A further object of the invention is to provide simple and efficient means whereby 75 it may be readily ascertained whether the ribbon will remain inactive or what field or zone of the ribbon is to be presented to the printing point.

With these and other objects in view, 80 the invention will be hereinafter more particularly described with reference to the accompanying drawings, which form a part of this specification, and will then be pointed out in the claims at the end of the description.

In the drawings, Figure 1 is a fragmentary vertical section of a typewriting machine, showing in elevation one form of my invention applied thereto. Fig. 2 is a fragmentary front elevation of the upper part of the machine shown in Fig. 1. Fig. 3 is an inverted plan of the ribbon vibrating mechanism removed from the machine. Fig. 4 is a plan view showing the position 95 of the parts when the actuating lever or member has been shifted with relation to its supporting and actuating member in order to move the vibrator to present one zone or field of the ribbon to the printing 100 point. Fig. 5 is a view similar to Fig. 4 except that the actuating member has been moved to a position to throw the ribbon over the printing point. Fig. 6 is a longitudinal section through the device taken on 105 the line VI—VI of Fig. 5. Fig. 7 is a detail plan of the vibrator cam lever and actuating member. Fig. 8 is a fragmentary

front elevation, partly in section, the section being taken transversely of the machine immediately in front of the vibrator. Fig. 9 is a fragmentary sectional plan through the vibrator and taken through the line IX-IX of Fig. 8. Fig. 10 is a fragmentary plan view showing the adjustable device which is mounted upon the rocking frame and serves as a means for moving the vibrating mechanism; and Fig. 11 shows a different form of ribbon vibrator arm.

While I show the invention as applied more particularly to a typewriting machine in which the carriage and platen are folded forward, it will be understood that the invention may be applied to other forms of machines.

The frame 10 has a rear member 11 and side members 12, and supported between the side members 12 are transversely extending rods 13. As shown there are three rods arranged in parallel relation and each rod is adapted to support a bank or set of key-levers 14. These key-levers 14 are suspended from the rods 13 and at one end have the usual operating key and adjacent to the pivot may be held by a spring 15 to a transversely extending plate 16 tending normally to force the outer end of the key-levers upward. Each key-lever at its inner end may be connected by a link 16^a or otherwise to a type bar (not shown), and each key-lever is adapted to engage a part 17 of a universal bar 18. The universal bar 18 has upwardly extending arms 19 and these arms at their upper ends are pivoted to the arms 20 of bell-crank levers 21. There are two levers 21 which are located at the rear and on opposite sides of the machine. Each bell-crank lever 21 is pivoted at 22 to a suitable part of the frame and has an end 23 which is adapted to engage a slot 24 located in the vertical arms 25 of a rocking frame 26. This rocking frame has two vertical arms 25 which are pivoted to rock on a transversely extending rod 27 at their lower ends and at their upper ends said arms 25 are connected by an integral and transversely extending bar or plate 28. The rod 27 is held at its outer ends in arms 29, which latter are held to a rod or shaft 30, and these arms are adapted to be operated by suitable platen-shift mechanism (not shown), to adapt the rocking frame to be elevated.

The rod 27 is connected at its ends to vertically movable posts or slides (not shown) which are movably held at their upper ends in bearings or guides 31, and each post or slide is secured to a bar 32. These bars 32 have similar bars (not shown) pivoted thereto, at 33, and to these latter bars, is held a carriage bed 34 along which the carriage 35 is adapted to travel in the usual way, said carriage being provided with a

suitable platen 36 about which the work sheet is adapted to be held. The carriage 35 and carriage bed 34 is adapted to be folded over and forward with the pins 33 as a pivot so that the platen 36 will rest upon the forward part of the frame of the machine and so as to substantially overhang the keyboard of the machine and in such a way as to reduce the cubical contents of the machine to make the same more compact when not in use for transportation or other purposes. The parts thus far described are not claimed specifically herein and may be of any suitable or preferred construction.

A bracket 37 has a transversely extending arm 38 in which are openings 39. Screws 40 have their bodies passing through said openings and have their threaded portions engaging threaded apertures in the carriage bed so as to rigidly hold the bracket 37 to the bed. This bracket has a forwardly extending arm 41 which connects with an integral and horizontally arranged arm 42 which extends substantially parallel to the arm 38 but is slightly higher than said latter arm. The arm 42 of the bracket 37 has a slot 43 extending lengthwise thereof, and adapted to enter said slot is a roller 44 carried by a pin 45 which extends downward as a projecting part from the arm 46 of a ribbon vibrator 47. The vibrator arm 46 is vertically arranged and has a part bent or folded upon itself, as at 48, so that the pin 45 may be rigidly held therein. The vibrator 47 has a horizontally extending arm 49. This arm 49 is enlarged at one end, as at 50, and is provided with a slot 51 through which the ribbon may be passed and intersecting said slot is a short slot 52 by which the ribbon may be readily threaded into the vibrator. The vertically extending arm of the ribbon vibrator terminates in a boss or part 53 which is pivoted by means of a screw 54 to an upwardly extending and integral curved arm 55 of the bracket 37. By this means the end 50 of the ribbon vibrator may be moved up and down with the screw 54 as a pivot to cause the ribbon to cover and uncover the printing point, and the vibrator guided by the slot 43 and roller 44, so that the ribbon vibrator will be suitably held while being moved on its pivot.

To operate the ribbon vibrator to permit different zones or fields of the ribbon to be presented to the printing point and to positively operate the ribbon vibrator in both directions to cover and uncover the printing point or to permit the vibrator to remain inactive in order that stencils may be made, various means may be employed. As shown, an actuating member or device is provided, and this member is pivoted by a screw 57 to a lug or projection 58 of the bracket 37, the said lug forming an extension of the horizontally arranged bracket

arm 42. The actuating member 56 is substantially L-shaped in form and has a cam lever or member 59 pivoted thereto as by a screw 60, said lever 59 serving as an adjustable connection between the actuating member and the vibrator. The screw 60, when the parts are in their normal position and the ribbon below the printing point, is axially arranged with respect to the pin 45 of the ribbon vibrator. A roller 61 is held on the pin 45 under the roller 44 and this roller is adapted to move between vertical walls 62 and 63 of the lever 59. The walls 62 and 63 may be inclined and are adapted to be adjusted in proper relation to the roller 61, and said walls form substantially a guide or raceway for the roller during the reciprocatory or swinging movement of the lever with the actuating member 56 as will be presently described. The actuating member 56 is adapted to be moved inward and outward on its pivot screw 57 and in doing so will carry the lever 59 therewith. The lever or adjustable connection 59 is capable of a plurality of adjustments. In one adjustment the walls 62 and 63 are so positioned with respect to the pivot screw 57 that the actuating member with its lever may be moved without moving the ribbon vibrator. If the lever is moved to the position shown in Figs. 4, 5 and 7, the walls of the lever become cam surfaces so that by vibrating or swinging the member 56 on its pivot to carry the lever therewith, the said walls will force the roll 61 inward and thereby throw the end 50 of the vibrator with the ribbon upward, and on the return of the member 56 will bring the ribbon held by the vibrator again below the printing point to its normal position, thus positively moving the vibrator in both directions. The vibrator with the rolls 44 and 61 is thus held in its movement between the walls 62 and 63 of the lever or adjustable connection 59 and the slot 43 of the bracket, the walls 62 and 63 being arranged at an angle with respect to the guiding slot 43 of the bracket. The actuating member or lever 56 is provided with a vertical portion 64 which is formed by cutting away a part of said actuating member to provide a slot 65 through which the end of the lever 59 may be passed. The lever 59 has a finger portion 66 on the outside of the vertical part 64 of the actuating member 56 and is adapted to engage cam portions 67 of the part 64 so as to hold said lever 59 in any one of its adjustments. The lever 59 may be of spring steel tending normally to frictionally engage the under surface of the cam portion 67 of the parts 64 and is provided with an enlarged part 68 in which is an opening 69 to adapt any one of a plurality of disks 70 to be readily seen through said opening according to the position of said lever. There are three disks shown, one lettered S to indicate stencils, the other lettered B to indicate the black portion of the ribbon, and the third lettered R to indicate the red portion of the ribbon, though these characters may be changed according to the nature of the ribbon and whether or not it is to have a plurality of fields or a single color, or drops of paint or other means may be used instead of the disks. When the lever is moved to the position shown in Figs. 5 and 7, the vibrator in this case will be moved to present the black portion of the ribbon to the printing point, and when moved over the disk R, a greater movement will be given to the ribbon owing to the greater inclination of the walls 62 and 63 and consequently the cam action thereof. This will present the red portion of the ribbon to the printing point, and when the lever is moved so that the letter S is seen through the opening 69 the walls 62 and 63 will be so positioned with respect to the pivot screw 57 that the said actuating member 56 with its lever or adjustable part may be moved without operating the vibrator and consequently the ribbon will remain inactive and below the printing point to adapt stencils to be made. The actuating member 56 is provided with a lug 71 and this lug is provided with an opening in which is fastened one end of a spring 72. The spring 72 has its other end fastened to a lug 73 forming a part of the horizontal bracket arm 42, said spring tending normally to force the actuating member 56 to its normal position and to prevent the ribbon vibrator and actuating member from becoming displaced when the carriage and bed are moved to a folded or compact position. The bracket 37 is provided with a forwardly extending arm 74 which is adapted to be engaged by a stop or part 75 carried by the actuating member 56 and which part by engagement with the arm 74 determines the normal position of the actuating member, the said part 75 being bendable to permit ready adjustment of the actuating member 56. The bracket arm 74 is long enough to extend under the actuating member 56 and serves as a guide for said member in its swinging movement. As a means to operate the actuating member 56 and to swing the same on its pivot screw 57 a device 76 is provided. This device 76 has a plate portion 77 which has a plurality of slots 78 through which pass screws 79 and by which said plate portion may be adjustably and rigidly held to the transverse bar 28 of the rocking frame 25. The device 76 has a bendable arm 80 located at one side of the plate portion 77 and which projects from one end and lies substantially parallel to said portion. A pin 80^a extends upwardly from the outer end of the arm 80 and is adapted to enter a slot 81 located in

the arm 82 of the actuating member 56. It will be evident that when the bar 28 is rocked on the depression of any one of the key-levers through the universal bar 18 that such movement will by reason of the engagement of the pin 80^a with the actuating member 56 rock the latter on its pivot and through said actuating member move its lever 59 and thereby cause the several movements of the ribbon vibrator as already explained. It will be further evident that the arm 80 may be bent forward and backward and thereby make the pin 80^a register properly with the slot irrespective of any arrangement of the location of the rocker bar 28 in relation to the carriage bed plate, it being understood that the pin 80^a may be bendable if desired.

In the construction of the mechanism herein shown the point of separation is between the device 76 and the actuating member 56 so that substantially the entire mechanism may be assembled independent of the machine and then applied thereto, such parts thus remaining in fixed relation both in the folded and working position of the carriage and its support. This arrangement permits ready adjustment and alignment and all that is necessary to properly position the parts in assembling the machine is to adjust and then fix the device 76 in its proper position.

Instead of forming the vibrator with a single slot for the ribbon, the horizontally arranged arm may have a substantially U-shaped end 82^a. This end has two upright portions or arms 83 and 84 in each of which is a vertical slot 85. These slots are intersected by short slots through which the ribbon may be threaded. The arms 83 and 84 are located on opposite sides of the printing point and support the ribbon at two points instead of one as in Figs. 1 and 2.

From the foregoing, it will be seen that simple and efficient mechanism is provided which is adapted to move a ribbon to cover and uncover the printing point and which is adapted to permit the machine to be used for making stencils; that the ribbon vibrator is positively held and guided and is positively moved to carry the ribbon both over the printing point and away therefrom; that simple and efficient means is provided whereby various throws of the ribbon may be obtained; and that simple and efficient mechanism is provided which may be readily made and assembled and which is particularly adapted for machines in which the carriage is foldable into compact relation to another part of the machine.

Having thus described my invention, I claim as new and desire to secure by Letters Patent:—

1. In a typewriting machine, the combination of a support, a bracket held to said

support, a ribbon vibrator pivotally held to said bracket, an actuating member pivotally held to the bracket, a lever pivotally held to the actuating member to adapt said lever to be relatively adjusted thereon, means forming a sliding connection between the lever and the vibrator, a rocking bar, and an adjustable device mounted on the rocking bar and having a pin-and-slot connection with the actuating member. 75

2. In a typewriting machine, the combination of a support, a bracket held to said support, a ribbon vibrator pivotally held to said bracket, an actuating member movably held to the bracket, a lever pivotally held to the actuating member to adapt said lever to be adjusted thereon, means forming a sliding connection between the lever and the vibrator, a rocking bar, and a device mounted on the rocking bar and having a connection with the actuating member. 80

3. In a typewriting machine, the combination of a support, a bracket held to said support, a ribbon vibrator pivotally held to said bracket, an actuating member pivotally held to the bracket, a member pivotally held to the actuating member to adapt the same to be adjusted thereon to different positions, means forming a connection between the second member and the vibrator, and means 90 for operating the actuating member. 95

4. In a typewriting machine, the combination of a bracket, a ribbon vibrator pivotally held to said bracket, an actuating member pivotally held to the bracket, a second member movable with the first-mentioned member and adjustable relatively thereto and having a connection with the vibrator to operate the same, and means having a pin-and-slot connection with the actuating member to operate the same. 100

5. In a typewriting machine, the combination of a ribbon vibrator, a pivotally held actuating member, an adjustable member mounted on said actuating member and forming a continuous connection between said vibrator and the actuating member, means for moving the actuating member, and means for adjusting the adjustable member whereby the vibrator may be given 110 different throws or permitted to remain inactive. 115

6. In a typewriting machine, the combination of a ribbon vibrator, a pivotally held actuating member movable transversely of the vibrator, an adjustable member pivotally mounted on said actuating member and forming a direct connection between said vibrator and the actuating member, and means for moving the actuating member whereby the vibrator may be given 120 different throws. 125

7. In a typewriting machine, the combination of a ribbon vibrator, a movable actuating member, and an adjustable lever 130

- mounted on the actuating member and forming a direct sliding connection between the actuating member and the vibrator transversely of the plane of movement of said 5 vibrator and adapted when given different adjustments to cause the vibrator to be given different movements and to be positively moved to and from the printing point.
10. In a typewriting machine, the combination of a ribbon vibrator, a movable actuating member, and adjustable means having projecting substantially parallel walls forming a direct connection between the actuating member and the vibrator adapted when given different adjustments to cause the vibrator to be given different movements or to remain inactive.
15. In a typewriting machine, the combination of a ribbon vibrator, a normally stationary support, and an actuating member held to said support and having an adjustable and positive cam connection with the vibrator and adapted when the connection is 20 adjusted to cause the ribbon to be given different throws or to remain inactive.
25. In a typewriting machine, the combination of a ribbon vibrator, a normally stationary support, and an actuating member held to said support and movable transversely of the plane of movement of the vibrator and having an adjustable bodily movable and direct sliding connection with the vibrator at all times mounted thereon and adapted when the connection is 30 adjusted to cause the ribbon to be given different throws and to be positively moved to and from the printing point.
35. In a typewriting machine, the combination of a ribbon vibrator, a normally stationary support and a movable actuating member mounted on the support and having a pivotally held and direct cam-like sliding connection with the vibrator and adapted 40 when the connection is adjusted on its pivot to cause the ribbon to be given different throws or to remain inactive.
45. In a typewriting machine, the combination of a ribbon vibrator, a movable member, a lever pivoted to and carried wholly by said member and having a sliding connection with the vibrator, and means for operating said member.
50. In a typewriting machine, the combination of a bracket having a slot, a vibrator pivotally held to said bracket and having a part thereof guided in said slot, a member having a sliding connection with the part of the vibrator passing through the slot of the bracket and so arranged with respect to said slot as to move transversely of the slot and to loosely confine a part of the vibrator, and means for actuating said member.
55. In a typewriting machine, a movable ribbon vibrator, and a lever movable to different positions with respect to the vibrator and having walls for engagement with a part of the vibrator and adapted to impart different throws to the vibrator or to permit it to remain inactive, and means for moving 60 the lever bodily.
65. In a typewriting machine, a movable ribbon vibrator, a normally stationary support, and a horizontally adjustable and bodily movable member pivotally held to said support and directly connected to said vibrator at all times and adapted to impart different throws to the vibrator and to positively move the ribbon to and from the printing point.
70. In a typewriting machine, the combination of a support having a slot, a ribbon vibrator pivotally held to the support and provided with a part projecting through the slot, an adjustable lever adapted to engage 75 the projecting part of the vibrator under the slot of the support and adapted to permit the vibrator to be moved to different distances or to permit the vibrator to remain inactive according to its adjustment, and means for reciprocating the lever.
75. In a typewriting machine, the combination of a support having a slot, a ribbon vibrator pivotally held to the support and provided with a part projecting through the slot, a member pivotally held to the bracket, a lever pivoted to the bracket and adapted to engage the projecting part of the vibrator under the slot of the support, said lever being 80 so arranged with respect to the slot of the bracket as to move transversely of said slot and adapted to permit the vibrator to be moved to different distances or the vibrator to remain inactive, and means for bodily moving the lever.
85. In a typewriting machine, the combination of a bracket having a slot, a vibrator pivotally held to the bracket and provided with a part projecting through the slot, an adjustable lever adapted to engage the same 90 projecting part of the vibrator under the slot of the bracket and so arranged with respect to said slot as will permit the vibrator to be moved to different distances or the vibrator to remain inactive, an actuating and supporting member for the lever, key-operated levers, and means including a pin-and-slot connection between the key-operated levers and the lever actuating member.
95. In a typewriting machine, the combination of a support, a bracket held to said support, a ribbon vibrator pivotally held to the bracket, an actuating member pivotally held to the bracket, a lever pivotally held to the member, means for holding the lever in various positions on the actuating member, means forming a sliding connection between the actuating member and the ribbon vibrator, said means being adjustable to cause 100 the vibrator to remain inactive in one position.

tion and to have different throws according to the other positions of said lever, and means for moving the actuating member.

20. In a typewriting machine, the combination of a support, a bracket held to said support and provided with a slot, an actuating member pivotally held to the bracket, a lever pivotally held to the bracket and provided with vertically extending walls forming a cam and guide way, means for holding the lever in various positions on the actuating member, a projecting part on the vibrator having rollers entering the slot of the bracket and the cam way of the lever, and means for operating the actuating member.

21. In a typewriting machine, the combination of a ribbon vibrator, an actuating member for moving the vibrator, a rocking bar, an adjustable device mounted on said bar and having a positive and separable connection with the actuating member to positively move the same in opposite directions, key-operated levers, and connections between the key-operated levers and said device for operating the latter on the depression of said levers.

22. In a typewriting machine, the combination of a ribbon vibrator, an actuating member for moving the vibrator, a rocking bar, and a device mounted on the bar and having a positive and separable connection with the actuating member to positively move the same in opposite directions.

23. In a typewriting machine, the combination of a carriage bed, a bracket securely held to said bed and provided with a horizontal and transversely extending arm having a slot extending lengthwise of said arm, a substantially L-shaped actuating member pivotally held to the bracket, a ribbon vibrator having a horizontally extending arm adapted to hold the ribbon at one end and a substantially vertical arm, an upwardly extending arm forming a part of the bracket and to which the vibrator is pivotally held, a lug carried by the bracket, a lug carried by the actuating member, a spring connected to the lugs and tending normally to force the actuating member in one direction, a connection between the actuating member and the vibrator, said connection being adjustable to cause the vibrator to remain inactive or to have different throws imparted thereto when the actuating member is operated, and means for operating the actuating member.

24. In a typewriting machine, the combination of a carriage bed, a bracket securely held to said bed and provided with a horizontal and transversely extending arm having a slot extending lengthwise of said arm, a substantially L-shaped actuating member pivotally held to the bracket, a ribbon vibrator having a horizontally extending arm

adapted to hold the ribbon at one end and a 65 substantially vertical arm, an upwardly extending arm forming a part of the bracket and to which the vibrator is pivotally held, a spring tending normally to force the actuating member in one direction, a lever forming a sliding connection between the actuating member and the vibrator, said lever being adjustable to cause the vibrator to remain inactive or to have different throws 70 imparted thereto when the actuating member is operated, and means for operating the actuating member.

25. In a typewriting machine, the combination of a support, a bracket secured to said support, a vibrator pivotally held to the 80 bracket, an actuating member pivotally held to the bracket, a lever pivotally held to the actuating member and having its body portion of spring metal and provided with a finger portion to manually operate the same 85 and with an enlarged part providing an opening therethrough, means mounted on the actuating member to indicate the position of the lever and consequently the throw of the vibrator to determine the part 90 of the ribbon moved over the printing point, a retaining portion formed integral with the actuating member and providing a slot for the passage of the lever and having a cam surface on the under side thereof adapted to 95 hold the lever in its different adjustments, and means for operating the actuating member.

26. In a typewriting machine, the combination of a bracket, a vibrator pivotally held to the bracket, an actuating member pivotally held to the bracket, a lever pivotally held to the actuating member and having its body portion of spring metal and provided with a finger portion to manually operate the same, means mounted on the actuating member to indicate the position of the lever and consequently the throw of the vibrator to determine the part of the ribbon moved over the printing point, means 100 formed integral with the actuating member adapted to hold the lever in its different adjustments, and means for operating the actuating member.

27. In a typewriting machine, the combination of a bracket having a forwardly extending engaging arm, a ribbon vibrator pivotally held to said bracket, an actuating member provided with a stop adapted to engage said arm to position the actuating member, means forming a connection between the vibrator and actuating member, a spring tending to force the stop of the actuating member against the arm of the bracket, and means for operating the actuating member.

28. In a typewriting machine, the combination of a bracket having an engaging arm,

- a ribbon vibrator held to said bracket, an actuating member provided with a stop adapted to engage the arm to position the actuating member, means forming a connection between the vibrator and actuating member, means tending to force the stop of the actuating member against the arm of the bracket, and means for operating the actuating member.
- 10 29. In a typewriting machine, a foldable support, a ribbon vibrator movably held on said support, an actuating member held to said support and positively and operatively connected to the vibrator at all times, said actuating member being adapted to move the vibrator in both directions and to impart different throws thereto, a rocking bar, and a positive and separable connection between the actuating member and the rocking bar.
- 15 30. In a typewriting machine, a support, a carriage adapted to travel along said support and foldable forward with the support into compact relation to another part of the machine to occupy less space than when in use, a ribbon vibrator pivotally held to the support, means a part of which is foldable with the support and carriage for moving the vibrator, key-operated levers, and means coöoperating with said levers and positively connected to and separable from the remainder of the vibrator moving means and adapted to operate the latter when the levers
- are operated and only when the carriage is in its normal working position.
31. In a typewriting machine, a support, a carriage adapted to travel along said support and movable with the support into compact relation to another part of the machine, two movable members partaking of the compact movement of the carriage and support, means for moving the members relatively to each other, a ribbon vibrator operatively connected to the members, key-operated levers and a positive and separable connection between the members and said levers.
32. In a typewriting machine, the combination of a ribbon vibrator, means for moving the vibrator, and a device having a bendable arm having a pin adapted to engage a part of the vibrator moving means to operate the latter.
33. In a typewriting machine, the combination of a ribbon vibrator, means for moving the vibrator having a slot, and an adjustably held rocking device having a bendable part provided with a pin adapted to engage the slot of the vibrator moving means to operate the latter.

This specification signed and witnessed this tenth day of August, A. D. 1912.

OTTO PETERMANN.
